(57) **CLAIM**

The ornamental design for a finger watch, as shown and described.

DESCRIPTION

FIG. 1 is a front elevational view of a finger watch, showing a first embodiment of our design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a perspective view thereof; and,

FIG. 8 is a front elevational view thereof in relation to a human hand.

The broken line showing of the individual's hand in FIG. 8 is for illustrative purposes only and forms no part of the claimed design.
